189,847

ACOUSTIC TILE OR SIMILAR ARTICLE

Philip M. Brody, Scarsdale, and Frederic H. Rahr, New York, N.Y., assignors to Wood Conversion Company, St. Paul, Minn., a corporation of Delaware

Filed Mar. 25, 1960, Ser. No. 59,869

Term of patent 14 years

(Cl. D18—2)

Fig. 1

Fig. 2

Fig. 1 is a front face view of an acoustic tile or similar article showing our new design; and

Fig. 2 is an enlarged fragmentary view taken substantially on the line 2—2 of Fig. 1.

The Fig. 1 disclosure has been shaded to represent contrast.

We claim:

The ornamental design for an acoustic tile or similar article, substantially as shown and described.
